(57) **CLAIM**

We claim the ornamental design for a lantern device, as shown and described.

DESCRIPTION

FIG. 1 is a front perspective view of a first embodiment of the claimed design;

FIG. 2 is a front view of the embodiment of FIG. 1;

FIG. 3 is a rear view of the embodiment of FIG. 1;

FIG. 4 is a left side view of the embodiment of FIG. 1;

FIG. 5 is a right side view of the embodiment of FIG. 1;

FIG. 6 is a top view of the embodiment of FIG. 1;

FIG. 7 is a bottom view of the embodiment of FIG. 1;

FIG. 8 is a front perspective view of a second embodiment of the claimed design;

FIG. 9 is a front view of the embodiment of FIG. 8;

FIG. 10 is a rear view of the embodiment of FIG. 8;

FIG. 11 is a left side view of the embodiment of FIG. 8;

FIG. 12 is a right side view of the embodiment of FIG. 8;

FIG. 13 is a top view of the embodiment of FIG. 8; and,

FIG. 14 is a bottom view of the embodiment of FIG. 8.

The broken line showing of the lantern device represents unclaimed portions of the article and forms no part of the claimed design. Broken lines formed by equal length dashes show unclaimed portions of the design. Broken lines formed of unequal length dashes (i.e. dash-dot) show boundaries between claimed and unclaimed portions of the design.
